(57) **CLAIM**

The ornamental design for a filter core for pot, as shown and described.

DESCRIPTION

FIG. 1 is a front elevation view of a first embodiment of a filter core for pot showing my new design;

FIG. 2 is a rear elevation view of the filter core for pot;

FIG. 3 is a left side elevation view of the filter core for pot;

FIG. 4 is a right side elevation view of the filter core for pot;

FIG. 5 is a top plan view of the filter core for pot;

FIG. 6 is a bottom plan view of the filter core for pot;

FIG. 7 is a top, front, left side perspective view of the filter core for pot; and,

FIG. 8 is a bottom, front, left side perspective view of the filter core for pot.

The broken lines showing portions of the filter core for pot form no part of the claimed design.

1 Claim, 8 Drawing Sheets
